UNITED STATES PATENT OFFICE.

MORTON C. HUTCHINSON, OF WOODBURY, NEW JERSEY, ASSIGNOR, BY DIRECT AND MESNE ASSIGNMENTS, TO SOUTHWARK FOUNDRY & MACHINE CO., OF PHILADELPHIA, PENNSYLVANIA, A CORPORATION OF PENNSYLVANIA.

GAG AND STOCK-RELEASE FOR PUNCHING-MACHINES.

1,317,373.

Specification of Letters Patent. Patented Sept. 30, 1919.

Application filed October 14, 1916. Serial No. 125,556.

To all whom it may concern:

Be it known that I, MORTON C. HUTCHINSON, a citizen of the United States, residing at Woodbury, in the county of Gloucester, 5 State of New Jersey, have invented a new and useful Gag and Stock-Release for Punching-Machines, of which the following is a specification.

My invention relates to punching machines and machines of a similar character, 10 and consists more particularly in the novel construction and the novel arrangement of a gag and of a punch stock and novel means for controlling and actuating the gag and the punch stock.

One object of my present invention is to devise novel means to enable the punch employed in conjunction with a gag machine of the ordinary type to rest lightly on the 20 material to be punched after the punching of each hole. A lever or other controlling means is employed to effect the actuation of the main gag and to also control the stock release, and such lever is designed to be actuated by means best suited to the conditions 25 met with in practice, and while for purpose of illustration I have shown it as being adapted to be manually actuated, it may be automatically or mechanically actuated, as 30 desired.

A further object of my invention is to devise novel means for balancing the punch stock.

A further object of my invention is to devise a novel construction of punch stock, a 35 novel construction of punch head, a novel construction of stock release, a novel construction of a punch stock guiding device, and novel means for actuating such devices.

Other novel features of construction and 40 advantage will hereinafter more clearly appear in the detailed description of my invention.

For the purpose of illustrating my invention, I have shown in the accompanying 45 drawing a typical embodiment of it which in practice will give satisfactory and reliable results. It is of course to be understood that this embodiment is typical only and that the

various instrumentalities of which my invention consists can be variously arranged and organized and that my invention is not limited to the precise arrangement and organization of these instrumentalities as herein shown and described. 50

Figure 1 represents a side elevation of a punching or similar machine in conjunction with which a novel gag and stock release embodying my invention is employed.

Fig. 2 represents a front elevation, partly 60 broken away, of a portion of the machine.

Fig. 3 is a detail view taken at right angles to Fig. 2 and showing some of the parts in section and other parts in elevation.

Fig. 4 represents a plan view of a spring 65 yoke employed.

Fig. 5 represents in perspective and in detached position the gag.

Fig. 6 represents a side elevation of the punch stock.

Fig. 7 represents in perspective and in detached position the stock release and certain of its adjuncts. 70

Similar numerals of reference indicate corresponding parts in the figures. 75

Referring to the drawings:—

1 designates the frame or housing of the punching machine, which is constructed to form a yoke 2, and a standard 3, in which latter is journaled a driving shaft 4, which 80 is adapted to be driven by means of any desired source of power. The driving shaft 4 is provided with an eccentric 5, which effects the reciprocation of the punch ram 6 in the usual manner. The upper end of the punch 85 ram is provided in the usual manner with an extension, see dotted lines in Fig. 1, which effects the raising at the proper time and in the ordinary well known manner of the punch head 7, which reciprocates between 90 the guides 8, to which latter are connected the strips 9 in any desired manner.

The lower end of the ram 6 preferably terminates in a head or impact member 10, 95 preferably rounded, and which is normally guided within an aperture 11 in the head 7, the bore of said aperture at the upper end being of greater diameter, as at 12, and of

reduced diameter at its lower end, as indicated at 13. 14 designates the gag, which is provided at its bottom with the laterally extending guide flanges 15 on opposite sides 5 of the gag and the upper face of the gag is preferably of a concaved contour, as indicated at 16. The head 7 in proximity to the bore 12 of greater diameter is transversely recessed, as at 17, in order to receive the 10 guide flanges 15 of the gag 14.

18 designates my novel punch stock, which is provided at its upper end with an enlarged and preferably cylindrical head 19 and such head is preferably integral with a 15 plunger 20 of a reduced diameter which terminates in a threaded extension 21 of less diameter than the plunger 20. The head 19 of the punch stock has a working fit in the bore 12 and the plunger 20 has a working fit 20 in the bore 13.

22 designates a spring yoke having a centrally located aperture 23 therein of any desired contour and the arms of the yoke are provided with the hooks 24 to which are connected the springs 25, the upper ends of said springs being secured to hooks 26 carried by a fixed portion of the frame-work. The threaded extension 21 of the punch stock is adapted to pass through the aperture 23 25 and to receive the punch or die 27 which is connected to the threaded extension 21 by means of a nut 28. 29 designates a guide or stripper between which and the guide blocks 30 is placed the material 31 to be punched. 30 35 32 designates a stock release which comprises a plate or block 33, the forward end of which is recessed at 34 to conform to the contour of the plunger 20 of the punch stock, and at the sides of such recess the front end 40 is angularly faced off as at 35.

36 designates a rod having at one end a hub 37 provided with pins 38, which pass into the bifurcated rear end of the block 33, it being seen that the hub 37 is received in 45 the recess 39 formed at the rear end of the block. 40 designates a collar loosely mounted on the rod 36 and secured to such collar is a threaded rod 41 which is in threaded engagement with a lever 42, the lower end of which 50 is fulcrumed in a bracket 43.

44 designates a spring interposed between the collar 40 and the rear end of the stock 55 release block 33. The free end of the rod 36 is threaded to receive a nut 45. The gag 14 has connected therewith a bifurcated rod 46, which receives the lever 42 and is connected therewith by means of a pin 47, which passes through a slot 48 in said lever 42.

49 designates an actuating handle connected with the lever 42.

The operation of my novel gag and stock release will now be readily apparent to those skilled in this art, and is as follows:

In the position of the parts seen in Figs.

1, 2 and 3, the gag and stock release are in 65 position for punching the hole. The driving shaft 4 is continuously revolved. On the downward movement of the punch ram 6, the guide 29 which is in alinement with the holes of the punch in the material 31 rests 70 lightly on the material to be punched and as the head 7 moves downwardly, the gag 14 is brought into contact with the head 19 of the punch stock so that on a predetermined downward movement, the punch stock is advanced and the hole is punched in the material. During the downward stroke of the head 7, as soon as the lower end of the head 19 of the stock is above the laterally extending aperture 50 in the head 7, see Fig. 2, the 80 spring 44 will cause the stock release to move inwardly beneath the head 19.

On the rearward or up-stroke of the head 7 and the ram 6, the punch stock remains in its lowermost position until the stock release 33 engages the under face of the head 19, whereupon the punch stock is raised. The operator then moves the lever 42 outwardly, thereby allowing the punch stock to move downwardly in the punch head 7, 85 so that the die will be brought into close proximity with the holes to be punched, will rest upon the plate to be punched, and will be accurately alined with respect to the hole to be punched. This outward movement of the lever 42 also withdraws the gag 14 so that the forward or downward stroke of the ram 6 is ineffective to perform the punching operation since there is no operative connection between the head 10 100 of the punch ram and the punch stock.

It will be understood from the foregoing that the punch head 7 is slidably mounted for vertical movement and it is maintained in its uppermost position by means of a 105 weighted lever which is connected by a link to the punch head in the usual manner. The punch ram 6 is mounted on the cam shaft 4 so that as the cam shaft 4 revolves, the punch ram 6 is continuously being 110 raised and lowered. If the gag 14 is moved outwardly through the medium of the handle 49, then the punch ram 6 simply reciprocates in a vertical path and the punch head 7 remains in its normally uppermost 115 position.

When, however, the handle 49, lever 42, gag 14, and their adjuncts are moved inwardly so that the parts assume the position seen in Figs. 1 and 3, it will be apparent that when the punch ram 6 is moved downwardly, its head 10 will engage the concave upper face 16 of the gag 14, which is now interlocked with the punch head 7 and in the path of the downward movement 120 of said punch ram. The continued downward movement of the punch ram 6, (as will be understood from Fig. 2) will move

downwardly in unison the gag 14 and the punch head 7 until the bottom of the gag 14 contacts with the top of the head 19 of the punch stock 18. The punch stock 18 during the above operation has been resting stationary on the work 31, since it is freely slidable in the punch head 7, but as soon as the bottom of said gag 14 contacts with the top of said head 19, it will be apparent that a further downward movement of the punch ram 6, head 10, gag 14, and their adjuncts, will force the punch stock 18 downwardly, constituting the power stroke of the punch, and the punch 25 will be forced through the material 31 to be punched. Through the medium of the springs 25, the yoke 22 and the stock release 32, the punch stock 18 is withdrawn as the punch head 7 recedes, as will be evident to those skilled in the art.

It will be apparent that in accordance with my present invention, I provide a novel construction of a stock release and a single instrumentality for effecting the actuation of the gag and the stock release.

It will now be apparent that I have devised a novel and useful gag and stock release for punching machines, which embodies the features of advantage enumerated as desirable in the statement of the invention and the above description, and while I have, in the present instance, shown and described a typical embodiment thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a punching machine, the combination of a guide, a punch head movable therein, a punch ram, a punch stock carried by and movable to a limited extent in the punch head and having a head and also having a lower reduced end, a gag movable in the punch head to and from a position between the punch ram and the punch stock, a stock release movable in the punch stock, a single instrumentality connected with and arranged to actuate the gag and the stock release, an apertured spring yoke receiving the reduced lower end of the punch stock, and retractile springs connecting said yoke with the guide.

2. In a punch, the combination with the punch head, the ram, the gag, and means to actuate the punch head and the ram, of a punch stock loosely mounted in the punch head, a stock release comprising a plate movable in the punch head and adapted to

engage the punch stock, a lever pivoted to the punch head and operatively connected with the stock release and with the gag, the latter being adapted to be interposed between said ram and punch stock, and resilient means between the lever and the stock release to effect the movement of the stock release toward the punch stock, said stock release engaging said punch stock for the purpose of withdrawing the same as the punch head recedes.

3. In a punch, the combination with the punch head, the ram, the gag, and means to actuate the punch head and the ram, of a punch stock movably mounted in the punch head, said gag being adapted to be interposed between said ram and punch stock, a stock release comprising a plate laterally movable in the punch head and adapted to engage the punch stock for the purpose of withdrawing the latter as the punch head recedes, a rod movably connected with said plate, a pin and means loosely mounted on said rod, a spring between said pin and said plate, a lever fulcrumed to the punch and connected with said pin, and means to connect said gag with said lever.

4. In a device of the character stated, a punch head, a punch ram, a gag movable transversely in said punch head, a punch stock having a limited travel in said punch head with respect to said gag, the latter being adapted to be interposed between said ram and punch stock, and laterally movable means independent of said gag adapted to frictionally grip said punch stock on the upward stroke of said punch head to limit the relative movement of said punch stock and punch head.

5. In a device of the character stated, a punch head, a punch ram, means to operate said head and ram, a punch stock movably mounted in said punch head, a gag interposed between said ram and punch stock, a laterally extending tension member engaging said punch stock and placed under increased tension on the downward movement of said punch stock, and means to limit the relative downward movement of said punch stock with respect to said punch head.

6. The combination of a reciprocal punch head, a punch ram, a punch stock freely slidable in said head, a gag carried by said head and adapted to be interposed between said ram and punch stock, a laterally movable stock release, and a tension device for causing said stock release to engage said punch stock for withdrawing the same as said punch head recedes.

7. The combination of a reciprocal punch head, a punch ram, a punch stock freely slidable in said head, a gag carried by said

head and adapted to be interposed between said ram and punch stock, a laterally movable stock release, and a tension device for causing said stock release to engage said punch stock for withdrawing the same as said punch head recedes, in combination with an operating lever suitably fulcrumed, and connections from said lever to said gag

and stock release, said tension device being interposed between said stock release and 10 said lever.

MORTON C. HUTCHINSON.
